UNITED STATES PATENT OFFICE.

JOHN C. LANGILLE, OF NEWPORT, WASHINGTON.

AEROBOAT.

1,015,568.

Specification of Letters Patent.

Patented Jan. 23, 1912.

Application filed September 13, 1910. Serial No. 581,772.

To all whom it may concern:

Be it known that I, JOHN C. LANGILLE, a citizen of the United States, residing at Newport, in the county of Stevens and State 5 of Washington, have invented certain new and useful Improvements in Aeroboats, of which the following is a specification.

This invention relates to vehicles and particularly to a vehicle combining the principles of the motor-boat and the aeroplane, with the object of producing a structure capable of traveling at a high speed and having both the advantages of the aeroplane and the high speed motor-boat.

15 A particular object is to provide a motor-boat equipped with planes which may be so disposed as to exert a lifting force upon the boat and thus relieve the skin friction of the boat against the water, augmenting the 20 natural tendency of the boat to rise out of the water forward, when traveling at a high speed.

Other objects and advantages will be apparent from the following description, and 25 it will be understood that changes in the specific structure shown and described may be made within the scope of the claim without departing from the spirit of the invention.

30 In the drawings forming a portion of this specification and in which like numerals of reference indicate similar parts in the several views, Figure 1 is a side elevation of a boat embodying the principles of my invention, Fig. 2 is a view similar to Fig. 1, showing the boat under way and in the position which it then assumes, Fig. 3 is a front view showing the use of the catamaran and the arrangement of the planes, Fig. 4 is a 40 side elevation of a modified form of boat including a single hull and a monoplane structure, Fig. 5 is a front view of Fig. 4, Fig. 6 is a detail of the plane shifting mechanism, Fig. 7 is a transverse section of one 45 of the hulls amidships, Fig. 8 is a transverse section forward, Fig. 9 is a transverse section aft and just forward of the tail.

Referring now to the drawings, there is 50 shown a boat hull 5 which is considerably elongated, and which at its rearward end has a tapered tail 6. The hull is of the deadrise type, having side bottom portions 7 and 8 slanted upwardly and outwardly from the keel 9, and having only a slight incline, the 55 incline increasing forwardly to an area directly adjacent to the bow, where the boat

has a relatively large amount of freeboard, the sides extending upwardly in slight curvature as indicated at 10, from the keel to the gunwale. Throughout the major portion of the hull from the forward end of the tail 6 to the rearward portion of the small area 10 just referred to, the slanting bottom portions 7 and 8 meet the upwardly extending side portions 11 at sharp angles 12 and 60 at the extreme after-portion of the hull, these angles 12, where they extend into the tail 6, form sharp edges of the tail, the latter being reduced vertically on a sharp curve indicated at 13.

70 The tail shaft 14 extends through a tunnel 15 in the tail, and at its outer end carries a propeller 16 of high pitch.

Extending vertically through the hull at a point just forwardly of the forward end 75 of the tail, there is a rod 17 carrying a tiller 18 at its upper end and a balanced rudder 19 at its lower end. As will be seen from the drawings, the rise 11 of the hull at each side has its greatest vertical dimension at the forward end of the tail 6, the angle 12 extending from the extreme rearward end of the tail to a point close to the bow, and being slanted upwardly throughout its entire length, thus giving the bottom 80 of the boat its greatest transverse angle at the bow and its least transverse angle at the tail, where it has only a slight transverse convexity. The advantages of this shape 85 will be apparent from the following description.

A motor of a proper type is mounted in the hull, as indicated at 20, and is connected with the tail shaft.

90 Mounted upon the forward and rearward portions of the hull and at opposite ends of an intervening cockpit 21, there are a pair of upwardly extending supporting frames 22 and 23 in the upper ends of which there are mounted transverse bearings 24, 95 receiving shafts 25, carrying vertically disposed worm gears 26, meshing with worms 27 mounted in the uprights and carrying hand wheels 28. The shafts 25 are carried by sustaining apparatus 29, which, as shown, 100 are two in number, one for each supporting upright and each consisting of a pair of superimposed planes 30 extending transversely of the hull and having themselves slight transverse downward curvature. The 105 upper plane extends forwardly beyond the lower plane, as indicated at 31, and the 110

plants are connected by suitable braces 32 and tie wires 33. It will be seen that through the medium of the hand wheels 28, the shafts 25 may be shifted to vary the 5 angle of these sustaining planes.

In use, after the boat has attained a reasonable speed in the water, which, as will be understood, will cause the forward portion to rise from the water to a considerable 10 extent, the planes are shifted upwardly at their forward portions which exerts a lifting force upon the hull and tends to raise it farther from the water, thus reducing the skin friction of the hull against the 15 water. By reason of the slight transverse curvature of the rearward portion of the hull, the boat is in effect a hydroplane, and, upon attaining a proper speed, it will be observed that the greater portion of the 20 hull will be lifted from the water and sustained by the planes while the tail remains in the water and the propeller drives the boat.

In Fig. 3 there is shown the front elevation of a boat of the catamaran type in 25 which two hulls A and B are connected by a bridge structure C, upon which there is mounted a transverse motor D having oppositely extending shaft portions E each 30 carrying a gear 20', which gears mesh with the gears 21' on the shafts 22', said

shafts being carried by the hulls A and B, and suitably connected to propeller shafts, not shown. The sustaining planes extend across both hulls and laterally therebeyond 35 and are mounted to be adjusted as in the first described form.

In the third form of the invention, a single hull is shown with two monoplanes mounted for adjustment as above described. 40 What is claimed is:

The combination with a motor boat, of supporting frames rising from the motor boat, shafts extending transversely of the motor boat and having their ends pivotally 45 supported by the supporting frames, concavo convex lifting planes fixedly secured on the shafts, gear segments secured to and depending from the under sides of the planes, worm bearing shafts disposed in 50 mesh with the segments and having inwardly extending ends, and means secured on the inwardly extending ends of the worm shafts for rotating the worms to adjust the position of the lifting planes on their 55 pivot shafts.

In testimony whereof I affix my signature, in presence of two witnesses.

JOHN C. LANGILLE.
